ADJUSTABLE FISHING ROD SOCKET

Roger H. Wester, 1333 Illinois St., Sidney, Nebr.

Filed Jan. 14, 1965, Ser. No. 83,468

Term of patent 14 years

(Cl. D31—4)

FIG. 1 is a top plan view of an adjustable fishing rod socket, showing my new design;

FIG. 2 is a side elevational view of the new fishing rod socket, looking in the direction of the arrow 2 of FIG. 1; and

FIG. 3 is a side elevational view thereof looking in the direction of the arrow 3 of FIG. 1.

The side opposite that in FIG. 3 is a mirror image of the side shown in FIG. 3.

I claim:

The ornamental design for an adjustable fishing rod socket, as shown and described.
